UNITED STATES PATENT OFFICE

SVEND M. JORGENSEN, OF ELIZABETH, NEW JERSEY, ASSIGNOR TO THE SUPERHEATER COMPANY, OF NEW YORK, N. Y., A CORPORATION OF DELAWARE

DIRECT CONTACT DESUPERHEATER

Application filed June 18, 1928. Serial No. 286,366.

In modern engineering practice it is the usual custom in power plants to employ high pressure and high superheated steam boilers and engines. In some plants however it is the practice after the plant has been changed over from the old time boilers to the more modern ones to retain one or more of the lower pressure engines which are used occasionally for peak loads or in other emergencies. In some cases steam from the main boilers is also used for process work and the temperature of the steam for such work must frequently be considerably less than the temperature of the highly superheated steam furnished by the main boiler of the plant. In such cases it has become the practice to use desuperheaters in which the temperature of the highly superheated steam is reduced to the desired degree by cooling such steam with water. Such desuperheaters are of two types, namely, direct contact and indirect contact.

The present invention relates to direct contact desuperheaters and has for its principal object to provide a new and improved method of desuperheating, to improve upon the construction of such apparatus and to increase the efficiency thereof. As heretofore constructed it has been the usual practice with its particular type of desuperheaters to bring about the reduction of the steam temperature by injecting water into a body of steam, whose temperature is to be reduced, in the form of a spray from a suitably constructed nozzle. This method of procedure is subject to the objection that it is extremely difficult to maintain, at all times, in its most effective form, the spray of water under the varying conditions encountered. It is a characteristic of a spray nozzle for water that such nozzle will operate most efficiently only within certain limits of pressure or quantity of the water which passes through it. Increase or decrease of the water pressure or quantity beyond such limits will entirely change the character of the resulting spray. The water pressure and quantity will increase or decrease with any variation of the quantity or the pressure and the temperature of the body of steam into which the water is injected.

Due to the fact that there may be comparatively wide variations of the quantity or the pressure and the temperature of the body of steam, it is therefore at times quite difficult to keep the desuperheater operating properly to obtain the desired output of the de-superheated steam.

In view of the above a further object of the present invention is therefore to provide a new and improved construction for a direct contact desuperheater by means of which the objections above noted will be overcome.

The above and other objects of the present invention will appear more fully from the following more detailed description and by reference to the accompanying drawings forming a part hereof wherein Fig. 1 is a central vertical section taken on the line 1-1 of Fig. 2 through a desuperheater constructed in accordance with the principles of my invention; Fig. 2 is a central, horizontal section taken on the line 2-2 of Fig. 1; Fig. 3 is a section taken on the line 3-3 of Fig. 2; Fig. 4 is a central vertical section through a modified construction in which the desuperheater drum has its longitudinal axis located in a vertical plane; Fig. 5 is a section on the line 5-5 of Fig. 4; Fig. 6 is a view similar to Fig. 1 of a modification in which only a single inlet pipe is provided for the superheated steam and Fig. 7 is a section on the line 7-7 of Fig. 6.

As shown in the drawings the desuperheater comprises a drum 10 preferably of cylindrical shape, the ends of which are closed by the heads 11 and 12. Extending along the longitudinal center line of the drum and preferably terminating short of the ends thereof, is a vertical baffle 13, shown most clearly in Fig. 2 of the drawings. Located at each side of said baffle is a plurality of steam inlet pipes 14. Any desired number of such pipes may be employed. For the purpose of the present disclosure I have shown two sets of such pipes, each set consisting of a pair, each pair being located on opposite sides of the baffle and on opposite sides of the transverse center of the drum. These pipes are closed on their lower ends and at their upper ends project through the

wall of the drum and are provided with flanged coupling members which serve to connect the pipes to steam lines through which superheated steam from the boilers is lead to the desuperheater. Each pipe is provided with a plurality of laterally projecting nozzles 15, said nozzles being directed on each pair of pipes towards the nearest end of the longitudinal baffle as clearly shown in Fig. 2 of the drawings.

Water is introduced into the drum 10 through the flanged inlet 16, the water being supplied in sufficient quantity to partially fill the drum and maintain the water level there- 15 in substantially to the height indicated in Fig. 1 of the drawings by the line W. With the water at such level it will be seen that some of the nozzles 15 are submerged while others of such nozzles are located above the 20 water level.

At any suitable point along the top of the drum and preferably approximately at the transverse center line thereof, a steam outlet 17 is provided through which the steam of 25 lower temperature is led from the drum. In order to minimize the possibility of the liquid contents of the drum from being carried over with the steam through the outlet 17, a steam trap 18 is secured to the inner wall of 30 the drum adjacent to the outlet 17, said steam trap is closed on its lower side by the wall 19 and its vertical wall is provided with a pair of openings 20, one located on each side of the longitudinal baffle 13.

35 The manner in which the nozzles 15 are placed so that such nozzles face in opposite directions will insure a circulation of the water in the direction indicated by the arrows in Fig. 2. The openings 20 of the steam trap 40 are preferably located so that such openings face opposite to the direction of the flow of the water immediately below such openings.

With a device constructed as above described so that the major part of the superheated steam is injected directly into a body of water and preferably along horizontal lines, the flow of the steam through the water is through a comparatively long path and as a result quite an efficient heat transfer takes 45 place. As the water is at the boiling or evaporation temperature it is evaporated quite rapidly as the superheat of the steam is reduced. Regulation of the temperature of the outgoing steam can be very quickly and 50 readily accomplished by merely varying the water level in the drum. When it is desired to increase the temperature of the outgoing steam, the water level is lowered, whereas when it is desired to decrease the temperature, 55 the water level is raised. In the usual operation of the device it will ordinarily be found desirable to keep the temperature of the outgoing steam approximately constant. The present apparatus enables a constant temperature of the outgoing steam to be very read-

ily obtained automatically by the use of a thermostatic control located in the outlet pipe and governing the rate of admission of water through the flanged inlet 16. The rate of conversion of the water into steam with the 70 apparatus herein disclosed is fairly rapid so that variations in the rate of flow of the water to the desuperheater will quite quickly produce similar variations of the water level and a change in the proportionate amount of 75 steam introduced above and below the water level, and consequently a relatively rapid change in the rate of conversion of the water to steam.

In the form shown in Figs. 4 and 5 the superheater drum has its longitudinal axis in a vertical plane the drum 10^a is preferably cylindrical and has its lower end closed by a flanged head 11^a. A portion 12^a of the upper part of the drum is detachably connected to 80 the main body of the drum, the meeting edges of the drum sections being provided with flanges 20, bolted together by the bolts 21. Projecting downwardly through a central aperture of the upper drum section 12^a, is a flanged inlet pipe 14^a into which the superheated steam is introduced. Projecting laterally from the side of said pipe 14^a and arranged at spaced intervals both about the periphery of said pipe and at different vertical heights thereof, is a plurality of nozzles 15^a, the extremities of said nozzles being bent to extend substantially tangentially to the pipe's periphery. A flanged outlet 17^a for the desuperheated steam is provided adjacent to the top of the drum and extends laterally from the side wall thereof. A baffle 22 is interposed between the outlet 17^a and the nozzles 15^a to prevent steam from being projected directly through said outlet. 95

In the form shown in Figs. 6 and 7 only a single inlet pipe 14^b is provided, and in order to permit a sufficient number of nozzles 15^b to be provided, the pipe 14^b extends at an inclination, as clearly shown in Fig. 6 of the drawings. The pipe 14^b, as shown in Fig. 7, preferably extends along the longitudinal center of the drum and has secured to it the upwardly and downwardly projecting webs or wings 25, 26 respectively. The nozzles 15^b, as shown in Fig. 7, are arranged along each side of the pipe 14^b and the ends of said nozzles are bent to extend in opposite directions on each side of the pipe in order to secure a circulation of the water similar to that obtained with the form of construction shown in Figs. 1 to 3 of the drawing. The construction of the outlet 17 and steam trap 18 shown in Figs. 6 and 7 is substantially the same as that illustrated in Figs. 1 to 3. 110

It will be noted that in all forms of the invention some of the nozzles 15 are located below the water level while others of said nozzles are above the water level.

I claim:

1. The method of desuperheating superheated steam, which consists in continuously injecting a major portion of the superheated steam in a plurality of jets into a body of water at different distances below the surface level thereof while simultaneously passing, in a plurality of jets, a minor portion of such steam in a restricted zone above said surface, to cause it to blend with the desuperheated steam rising from said body of liquid.

2. The method of desuperheating superheated steam, which consists in continuously injecting a major portion of the superheated steam in a plurality of jets into a body of water at different distances below the surface level thereof while simultaneously passing, in a plurality of jets, a minor portion of such steam in a restricted zone above said surface, to cause it to blend with the desuperheated steam rising from said body of liquid and varying the proportion of said minor portion to said major portion in accordance with varying temperature conditions of the superheated steam in order to secure a delivery of the desuperheated steam of approximately uniform temperature.

3. In an apparatus of the character described, a container adapted to contain a body of water, and a plurality of nozzles in said container connected with a source of superheated steam, said nozzles being located in different parts of said container and having their jet orifices directed substantially in parallelism with the adjacent side wall of the container and the surface of said water, and pointing in different directions according to their location in order to cause a continuous circulation of said water about said container.

4. In an apparatus of the character described, a container adapted to contain a body of water, a baffle extending along the longitudinal center line of said container and a plurality of nozzles, connected with a source of superheated steam, arranged in groups on each side of said baffle with the jet orifices of said nozzles pointing in opposite directions on opposite sides of said baffle to cause the steam issuing therefrom to effect a circulation of the water within said container around said baffle and container.

5. In an apparatus of the character described, a container adapted to contain a body of water, a baffle extending along the longitudinal center line of said container and a plurality of nozzles, connected with a source of superheated steam, arranged in groups on each side of said baffle with the jet orifices of said nozzles pointing in opposite directions on opposite sides of said baffle to cause the steam issuing therefrom to effect a circulation of the water within said container around said baffle and container, certain of said nozzles of each group thereof being arranged below the surface level of the water

and the remainder being above said level.

6. In a desuperheater, a container adapted to contain a body of water, and a plurality of nozzles connected with a source of superheated steam, arranged in spaced relationship and distributed equally on opposite sides of the longitudinal central plane of said container, said nozzles having their jet orifices located below the surface level of the water and so directed with respect to said plane and to the side wall of the container nearest to each respective nozzle, that a continuous circulation of said water within said container is effected by the steam issuing from said orifices.

7. A desuperheater as set forth in claim 6 in which in addition to the nozzles on each side of the center plane and located below the surface of the water, a plurality of nozzles are provided with their jet orifices located above said surface.

8. A desuperheater comprising a closed container, means for continuously supplying water to said container for maintaining a body of water therein, a baffle extending along a longitudinal central plane of said container and terminating short of the ends thereof, a plurality of headers projecting into said container upon opposite sides of said baffle and a plurality of spaced nozzles projecting laterally from said headers, said nozzles being arranged to cause a circulation of the body of water within said container.

9. A desuperheater as set forth in claim 8 in which certain of said nozzles are located below the surface level of said water and the remainder thereof are located above said level.

10. A desuperheater comprising a container adapted to contain a body of water, a header adapted to be connected to a source of superheated steam projecting into said container, said header having its longitudinal axis inclined to the surface of said water and a plurality of nozzles projecting laterally from opposite sides of said header, certain of said nozzles being located below said surface for causing the superheated steam to be injected directly into said water and others of said nozzles being located above said surface for causing a portion of the superheated steam to be passed above said surface.

11. A desuperheater comprising a container adapted to contain a body of water, a header adapted to be connected to a source of superheated steam projecting into said container, said header having its longitudinal axis inclined to the surface of said water and a plurality of nozzles projecting laterally from opposite sides of said header, and a baffle extending substantially along a longitudinal central plane of said container.

12. In a desuperheater, a closed container, means for supplying water to said container

and maintaining a body thereof within said container, a header projecting into said container with its axis lying along substantially the longitudinal center line of the container and a plurality of nozzles projecting laterally from said header and spaced equally both longitudinally along, and transversely about, said header, certain of said nozzles lying below the surface of the water and the remainder of said nozzles being located above said level.

13. In a desuperheater, a closed container, means for supplying water to said container and maintaining a body thereof within said container, a header projecting into said container with its axis lying along substantially the longitudinal center line of the container and a plurality of nozzles projecting laterally from said header and spaced equally both longitudinally along, and transversely about, said header, certain of said nozzles lying below the surface of the water and the remainder of said nozzles being located above said level, said nozzles having their jet orifices directed substantially tangentially to the side walls of the header and of said container whereby the water will be caused to circulate by the steam issuing from said nozzles around said header and container.

30 In testimony whereof I have hereunto set my hand.

SVEND M. JORGENSEN.
